SMOKE ABATER

Filed Oct. 22, 1927

FIG. 1

FIG. 2

Inventor
WILLIAM KREFT

By: *Ben T. Zillman*
Attorney

UNITED STATES PATENT OFFICE

WILLIAM KREFT, OF ST. LOUIS, MISSOURI

SMOKE ABATER

Application filed October 22, 1927. Serial No. 227,893.

My invention relates to improvements in smoke abaters, and more particularly to a device of this character which will be neat and compact in appearance and construction, 5 simple, convenient, economical, sturdy, and efficient and satisfactory for use wherever found applicable.

One of the objects of my invention is to provide a device of the kind described, in 10 which any soot and other foreign matter that has accumulated within the device may be shaken out from time to time, as the occasions demand, and without opening the stack, with little effort.

15 Another of the objects of my invention is to provide a device of the kind described, which may be quickly, easily and conveniently placed into or removed from a smoke stack with which it co-operates, whenever so desired or found necessary, for the purpose 20 of repairing, inspecting, thorough cleaning or the like.

Another object of my invention is to so construct a device of the character described, 25 that the sizes and proportions of the parts will be such that the proper draft will be had, and so that the capacity of the stack at the point of installation of the abater will not be materially reduced.

30 Another object of my invention is to provide a device of the kind described, wherein the gases and solid particles carried through the stack will be given a somewhat tortuous path so that the solid particles will either 35 drop back down the stack or lodge in or on the device while the gases pass therethrough and out the stack.

Many other objects and advantages of the 40 construction herein shown and described will be obvious to those skilled in the art to which this invention appertains, from the disclosures herein given.

To this end, my invention consists in the 45 novel construction, arrangement and combination of parts herein shown and described and more particularly pointed out in the claims.

In the drawings, wherein like reference 50 characters indicate like or corresponding parts throughout the views,

Figure 1 is a vertical elevation, showing my improved device in place within a stack, some of the parts being shown in section; and

Figure 2 is a cross-sectional view, taken substantially along the line 2—2 of Fig. 1.

In the drawings, wherein I have indicated a preferred embodiment of my invention, there is shown a smoke stack A, of any suitable size, shape and material, the same being shown as being greatly enlarged at some point intermediate its ends, as at 1, this enlargement being provided so that the effective area through the stack at this point, after the smoke abater or filter is in place therein, will not be materially reduced, as compared to the effective area of the stack at points to either side of this enlargement. At the top of the stack there is mounted a cowl 2, for well-known purposes.

Another object of my invention is to so construct a device of the character described, 70 that the sizes and proportions of the parts will be such that the proper draft will be had, and so that the capacity of the stack at the point of installation of the abater will not be materially reduced.

75 A damper 3 is arranged within the stack, above the enlarged portion 1 thereof, said damper being connected to an operating lever 4, which is in turn operably connected to a rigidly mounted arm 5, by means of a coil spring 6, the spring acting to retrieve the damper to open position after any pivotal movement of the operating lever 4. A chain 7 is connected at one end to the free end of the lever 4, and the other end of the chain is extended to any suitable distant point, so that 80 a pull on the chain will act to close the damper, and upon releasing the pull, the spring will retrieve the damper to its open position.

85 A large opening 8 is formed through the side or wall of the stack at said enlarged portion, and a door is movably mounted on the stack so as to form a closure for said opening, as by hinges 10, or the like, said door being indicated at 9.

90 A support or rail 11 is mounted on the inside of the enlarged portion of the stack, and extends rearwardly and upwardly on an incline, away from said opening, said support having notches 12 adjacent its rear, for a purpose to be presently described.

95 The smoke abater per se, is indicated at B, and comprises a flat, box-like structure to form a container or receptacle having a bounding wall 13 of a shape or outline to conform to the shape of the stack interior at said 100

enlargement. Openings 14 and 15 are provided across the top and bottom, respectively, of the box, and in the embodiment shown, these openings or apertures are long and narrow. 5 These apertures are preferably so arranged that those along the top extend in a direction substantially perpendicular to the direction in which those at the bottom extend. In the drawing, these elongated apertures are shown as formed by placing a series of thin strips 16 across the top of the box, and a second series of strips 17 across the bottom of the box. Half of the series of strips 16, to one side of the center, are spaced parallel to one 10 another and are inclined from their lower to their upper parallel longitudinal edges, and the other half of the series 16, to the other side of the center, are similarly arranged, except that they are inclined in the opposite direction. The other set of strips 17, on the bottom of the box are divided into two groups in the same way, the only difference being that all of the lower strips extend in a plane parallel to and perpendicular to that in which the 15 upper strips extend.

Within the receptacle, in the space between the apertured top and bottom wall, I place a quantity of fire-proofed fibrous material, C, in such a way as to form a baffle or filter, to retard the passage of solid particles therethrough. A material that I have found highly desirable for the purpose is hemp that has been impregnated or otherwise suitably treated with water-glass solution, so that the hemp 20 thus initially treated will not burn out during service. I have found that potash water-glass or potassium silicate is best for this purpose. The hemp is arranged in strands, and placed in layers superimposed on one another, the 25 strands of hemp in the adjacent layers preferably extending in mutually perpendicular directions.

The gases flowing upwardly through the stack and carrying the solid particles of soot 30 and other foreign substances therewith, encounter the abater B, and as they have a tortuous path therethrough, most of these solid particles will either fall back into the bottom of the stack from whence they came, after 35 impinging against the under side of the baffle, or will be caught or lodged therein, while permitting the cleared gases to continue up through the stack.

If it is found desirable to remove the collection of soot and other foreign matter contained within the box, the same can be done either by removing the box itself from the stack, or by shaking the box while it is in the stack. To accomplish the latter, the box is 40 provided with lugs 18 adjacent the rear thereof, these lugs being adapted to be received in and engage with the grooves or notches 12 provided at the rear of the rail 11. As the box is slid back to its proper position within 45 the stack, the lugs will drop into the notches,

to thereby prevent any accidental sliding movement of the box relative to the rail. A chain 19 is connected at its end 20 to the forward end of the box, said chain passing over a pulley 21 arranged at some suitable point, 70 as upon an arm affixed to the stack, and shown as 22, the free end of the chain being conducted to any desired point. A pull upon the chain will lift or tilt the box about its rear knife edges, and a sudden release of the chain will cause the box to drop suddenly upon the supporting rail, to thereby shake out any solid particles that may have become lodged therein. This alternate or intermittent tilting and dropping movement of the box may be performed until the box is clear of sediment. 75

It is obvious that this soot dislodged by the shaking of the box would fly up the stack if there were no means provided to prevent this, and it was for this purpose that the 80 damper was provided within the stack. The damper is held in its closed position while the shaking is being done, by pulling upon the chain 7, and upon release of the chain the damper will be retrieved by the spring, 85 to its open position.

Inasmuch as the hemp thus treated with water-glass would be too brittle for withstanding handling and usage, this brittleness can be counteracted or prevented by the 90 use of graphite, preferably powdered, this graphite being used on the hemp either before or during its impregnation with the water-glass.

It may be mentioned at this point, that the 100 slope or inclination of the box transversely within the stack, is shown as being approximately 15° to the horizontal, this inclination having been found satisfactory, and that the area of the stack at the enlarged portion, 105 wherein the box is located, is approximately eight times as large as the area of the stack at either end of the enlargement. In this way there has been found to be no reduction in the effective area of the draft opening due to the space occupied by the box and contents, and the efficiency of the furnace will not be impaired by too little draft or choking. 110

Having thus described my invention, it is 115 obvious that various immaterial modifications may be made in the same without departing from the spirit of my invention; hence I do not wish to be understood as limiting myself to the exact form, construction, arrangement and combination of parts herein shown and described, or uses mentioned, except as limited by the claims.

What I claim as new and desire to secure 125 by Letters Patent is:

1. A smoke abater comprising a container having elongated narrow openings across the top and bottom thereof, said openings across the bottom extending in a direction trans- 130

verse to those openings across the top, and fire-proofed fiber in said container.

2. The combination with a smoke stack greatly enlarged intermediate its ends and provided with an opening through its side wall at said enlargement, a door covering said opening, a support within said stack at said opening and extending upwardly and rearwardly therefrom and provided with notches, of a smoke abater comprising a box adapted to be removably inserted into said stack through said opening and be slidably supported along said support, said box provided with lugs at the lower edge to engage with said notches to prevent accidental sliding movement of the box.

3. A smoke abater of the kind described, comprising a container having a series of elongated openings extending across the top and across the bottom thereof, all of the openings extending across the bottom being transverse to those extending across the top, and non-combustible material in said container between said top and bottom openings.

4. The combination with a smoke stack provided with an opening through its side wall, a door covering said opening, a support within said stack adjacent said opening and extending upwardly and rearwardly therefrom and provided with stops, of a smoke abater comprising a box adapted to be removably inserted into said stack through said opening and be slidably supported along said support, said box being provided with means co-operating with said stops to prevent accidental sliding movement of said box.
